UNITED STATES PATENT OFFICE.

DAVID GROVE, OF BERLIN, PRUSSIA, GERMANY.

STEAM COOKING APPARATUS.

SPECIFICATION forming part of Letters Patent No. 251,578, dated December 27, 1881.

Application filed August 17, 1881. (No model.)

To all whom it may concern:

Be it known that I, DAVID GROVE, of the city of Berlin, in the Kingdom of Prussia, in the Empire of Germany, have invented a new 5 and useful Improvement in Steam Cooking Apparatus for Military and other Purposes, of which the following is a specification.

My invention relates to improvements in transportable or stationary steam cooking apparatus for military or other purposes.

In the following specification I have explained the details of construction in which my invention consists, and have fully illustrated them in the accompanying drawings, in which—

15 Figure 1 represents a side elevation, partly in section; Fig. 2, a transverse section of Fig. 1; Fig. 3, a plan view, partly in section, on line *a* *b* of Fig. 1. Fig. 4 is a diagram representing the arrangement of the coils, hereinafter explained.

The apparatus shown in these drawings is represented as mounted upon wheels, and is portable, and specially adapted for military purposes.

25 The wheels *A A* in these drawings are represented as supporting suitable frame-work, driver's seat with springs, and appliances usually required in such a structure. The rear wheels are provided with a bent axle to give 30 room for the body, the front axle being straight and of ordinary construction.

The fire-box (represented in Figs. 1, 2, and 4 at *D'*) is composed of tubes or pipes, which at the same time form the box and grate and act 35 as heating-tubes for the water. The arrangement of these tubes is shown more clearly in Fig. 1. They are coiled within the fire-box, next to the wall thereof, and form an inner wall or lining for said box. The ends extend up-

40 ward and open into a water-space above, as shown in Fig. 1 at 22. The fire-box is located in rear of the hind axle and extends below it. The flue extends from the fire-box underneath the wagon to the front thereof, and there is 45 directed upward to the smoke-pipe. The flue below the wagon is provided with coiled pipes arranged in the same manner as those in the fire-box.

The water-pipes in rear of the axle on the 50 lower part of the fire-box are arranged, as shown in Fig. 1, to form a grate, which upholds the fuel

and admits air thereto. Along the flue or smoke chamber, arranged from the axle forward, the pipes are placed more closely together and all in the same line at the bottom. 55 Outside of this tubular fire-box and chamber is a sheet-iron casing, *K*, which completely incloses the whole, excepting at that portion where the air is admitted through the grate-bars. The coils are short, as shown in Fig. 4, 60 and may open alternately, one set on the right and the other on the left, into the water-chamber. These pipes being in sections, any part, when damaged, may be easily replaced.

The water-chamber is formed by the sheet- 65 metal casing *K'*, Figs. 1 and 2. Within this chamber are food-receptacles *L L* and *M M*, the two larger being arranged in front of the rear axle, and designed for cooking food for the rank and file, while the smaller are in rear of the 70 said axle, and may be used for cooking the food of the officers. They may be made with inclined bottoms, as shown in Fig. 2, for convenience in removing the food. These food receptacles or boilers are preferably made of such 75 size that the meals for half a battalion can be cooked at one time. They are provided with air-tight doors or lids *L'*, which may be pressed down to form a tight joint by means of eccentrics, screws, or any equivalent means, so that 80 when the vessels are used as boilers a suitable pressure may be attained. These covers *L'* are provided with hinges and handles for convenience in use. The hinges are attached to the central part, *n*.

85 A safety-valve may be provided for letting the steam into the chimney *H*. The pressure in the chambers for cooking purposes should never exceed more than one and three-quarters of ordinary atmospheric pressure.

90 A water reservoir or receptacle for feeding the apparatus (marked *P*) is placed over the forward wheels, and is provided with double-acting cock *p*, for supplying water to the apparatus when it is required to compensate for 95 the waste occasioned by the escape of steam. Not much water is required for this purpose, as the steam is for the most part condensed upon the walls of the receptacle.

A tool-box is provided, as shown at *R*, upon 100 one side of the apparatus next the driver's seat.

The shell or casing *K'* of the receptacle

should be so attached to the frame-work of the carriage that all loosening by jarring in transportation shall be avoided.

The space between the coils and the outer shell, K, may be filled with any suitable non-conducting material for the purpose of retaining heat within the chambers.

The exterior casing, of wood or other suitable material, (shown at F',) may be used to close the whole apparatus.

As represented in Figs. 1 and 3, the chimney H is pivoted over the central smoke-flue, and when the apparatus is not in use for cooking purposes this smoke-flue may be lowered to rest in the fork G upon the rear of the apparatus. It will be understood that sufficient quantity of water must be kept within the shell or casing to be in communication with the pipes which open within said casing. This constitutes the steam-chamber, and within it are placed the cooking-receptacles L M, as shown in Fig. 2, so that the steam acts upon the bottom, sides, and ends of these receptacles.

The tubes or pipes which form the upper part of the smoke-chamber, and just underneath the water-reservoir, are preferably arranged, as shown in Fig. 1, so that each third coil is in a plane lower than the two preceding and two following coils. These pipes give a large amount of heating-surface and an equal and rapid generation of steam, and the heat resulting therefrom is equally distributed over all the walls of the apparatus. Food is thus cooked in a very short time, and very few men are required to attend the apparatus.

A fire can be started while the apparatus is in motion, so that a very short time is required after arriving at bivouac to complete the cooking.

A fire-door, C, closes the fire-box, so that no fire is visible to the enemy, and in this respect

there is great advantage over the ordinary mode of cooking by open fires.

In case very light firing material be used, sparks may be extinguished by letting steam into the smoke-stack, or by any suitable spark-extinguisher applied to said smoke-stack.

It is evident that the apparatus may be used as a stationary one by dispensing with the wheels and locating it upon suitable foundation.

In case a separate compartment be not employed for the use of the officers, the cooking-chambers for the rank and file can be divided into four equal compartments.

This apparatus can also be adapted, without departing from the spirit of my invention, for use on board ship.

An ordinary water-gage, D, and manometer E may be used in connection with the apparatus.

Having thus described my invention, what I claim is—

1. A steam cooking apparatus consisting of a fire-box and flue having surrounding coils forming the walls and grate thereof, the water-chamber above said box and flue and in communication with said coils, the food-receptacles arranged above the water-chamber, all the parts being arranged as set forth.

2. The combination of the wheels A A and frame-work, as shown, bent axle, and fire-box composed of the bent tubes, water-chamber connected therewith, food-receptacles, and hinged smoke-stack, substantially as described.

3. The combination of the fire-box, the water-chamber, food-receptacles, and a water-supply, P, mounted over the forward wheels, substantially as described.

DAVID GROVE.
